UNITED STATES PATENT OFFICE.

SAMUEL M. BEERY, OF OMAHA, NEBRASKA, ASSIGNOR TO HIMSELF AND ISAAC MASON SMITH, OF SAME PLACE.

PLATFORM FOR RAILROAD-CARS.

SPECIFICATION forming part of Letters Patent No. 290,516, dated December 18, 1883.

Application filed October 22, 1883. (No model.)

To all whom it may concern:

Be it known that I, SAMUEL M. BEERY, of Omaha, in the county of Douglas and State of Nebraska, have invented a new and Improved 5 Platform for Railroad-Cars, of which the following is a full, clear, and exact description.

The object of this invention is to devise means whereby the space left between the ends of the platforms of cars as ordinarily constructed may be entirely closed, so that there will be no danger to passengers in passing from one car to the other; and to this end the invention consists, principally, in the employment of sliding platforms arranged for closing said space.

Reference is to be had to the accompanying drawings, forming part of this specification, in which similar letters of reference indicate corresponding parts in both the figures.

20 Figure 1 is an inverted plan view of the ends of the bottoms of two railroad-cars having my improved sliding spring-platforms applied thereto; and Fig. 2 is a sectional elevation of the same, taken on the line *x x* of Fig. 1.

25 A A represent the bottom boards of two railroad-cars, which boards are secured upon the edge timbers or sills B B.

Between the sills B B are secured the cross-timbers C C', to which are secured the parallel bars D D, between which the draw-heads of the cars (not shown) are held. In these cross-timbers C C' are fitted, also, the rods E E, which support the edges of the platforms 30 F F. These platforms F F are supported in the center upon the friction-rollers a a, placed upon and attached to the upper side of the parallel bars D D, as shown clearly in Fig. 2. The platforms F F are attached to the bars 35 E E by the staples b b, which are loose upon the bars E E, and the said bars E E are headed or hooked at their forward ends, as shown at c c, to prevent the platforms F F from being forced off from the bars E E by the action of 40 the springs G G, which are placed upon the rods E E between the cross-timbers C C' and the offsets d d, in the under side of the platforms F F, formed by making in the platforms the notches or cut-away places d' d', 45 as shown clearly in the drawings. The outer

edges of the platforms F F are faced with the bands e e, of iron, to prevent them from being jammed or splintered in coupling the cars, and each platform is provided at the edge with a friction-ball, f, held in the cup g, 55 and held in place by the band of iron e, the band being provided with a suitable hole, h, smaller than the ball, through which the ball protrudes a short distance, as shown clearly in the drawings, so that the balls will take the friction between the edges of the platforms F F at all times, and especially when the cars are rounding curves in the railroad. At the side edges the platforms F F are cut away to form the spaces j j, in which the steps to the cars 60 are to be fitted. The springs G G serve to constantly force the platforms F F outward upon the rods E E, and to hold them forced outward, so that when the cars are coupled the edges of the platform will come fairly together, thus closing all space between the cars, so that there will be no danger of stepping or falling between the cars in passing from one car to another.

In coupling the cars, the springs G G yield 75 and permit the platforms F F to slide backward sufficiently upon the rods E E to permit the couplers to come together to effect the connecting of the cars; and in rounding curves in the railroad, the springs also yield, 80 so that the platforms will not interfere with the free turning of the cars.

The rods E E may be held to the cross-pieces C C' by any suitable means, but I prefer to employ the staples k k, and to head or bend the 85 rear ends of the rods, as shown at l l, which hooks or heads come against the rear edges of the cross-pieces C C', where they are held by the staples m m, as shown in Fig. 2; or, instead of the staples k k, suitable boxes might 90 be used, and instead of the heads c c, I might use nuts screwed upon the forward ends of the rods.

Having thus described my invention, I claim as new and desire to secure by Letters Patent— 95

1. The combination, with a car-bottom, of the cross-timbers C C', carrying rods E E, the parallel bars D D, having side rolls a, and the spring-pressed platforms F, having offsets d and notches d', as shown and described. 100

2. The sliding platform F, supported in the center upon the friction-rollers *a a*, placed upon the bars D D, substantially as and for the purposes described.
3. The sliding platforms F, provided at their adjacent edges with the friction-balls *f*, substantially as and for the purposes set forth.
4. The platform F, placed upon the bars E E, and supported in the center upon the roll-

ers *a a*, placed upon the parallel bars D D', in combination with the springs G G, placed upon the rods E E, between the rear edge of the platform and the front of the cross-piece C', substantially as and for the purposes set forth.

SAMUEL M. BEERY.
